UNITED STATES PATENT OFFICE.

HERMAN T. ARENDS, OF HIGHLAND PARK, MICHIGAN.

MAGAZINE BINDER.

Application filed December 8, 1926. Serial No. 153,254.

The present invention relates to binding devices for sheets and more especially for magazines and periodicals although not confined to such materials.

5 Among the objects of the invention is a binder which may be quickly and easily applied to such materials to hold them securely.

Another object is a binder for magazines which while holding them securely and tightly nevertheless permits their being opened to substantially as flat position as before binding.

10 Other objects will readily occur to those skilled in the art upon reference to the following description and the accompanying drawings in which:

Figs. 1 and 2 are respectively a plan and side view of one member of one form of the invention;

15 Figs. 3 and 4 are similar views of another member;

Fig. 5 is a perspective view of the two members in co-operating relation;

20 Figs. 6 and 7 are respectively a plan and side view of one member of a second form of the invention;

Figs. 8 and 9 are similar views of another member;

25 Figs. 10 and 11 are similar views of another member;

Figs. 12 and 13 are similar views of a fourth member;

Fig. 14 is a perspective view of the four members in co-operating relation;

30 Fig. 15 is a section through a finished binder;

Fig. 16 shows a portion of a magazine prepared for binding;

Fig. 17 is a perspective view of a second modification.

The binder shown in Figs. 1 to 5 consists of two members telescoping to form a channel between the sides of which the backs of the magazines lie, which channel has inturned flanges adapted to fit into notches in the ends of the magazines, means being provided to hold the members firmly together after insertion of the magazines.

45 The member shown in Fig. 1 consists of a metal strip 20 having its sides turned up at right angles as at 21 and one end turned up and bent over as at 22 to form an inturned flange. At the other end short portions of the sides 21 are bent inwardly to form guide 50 and holding tabs 23 for the second member.

55 The second member as shown in Figs. 3 and

4 consists of a strip 25 of metal of such width as to slide readily between sides 21. One end of this strip is turned up and over to provide an inturned flange 26 and the other end is 60 provided with a tongue 27 adapted to slide through a slot 28 in end 22 of the first member and be bent over to firmly secure the parts together.

The form of device shown in Figs. 6 to 14 65 involves similar principles but is adjustable to provide for different sizes and numbers of magazines.

This form is made up of four members providing for adjustment in both length and 70 width.

75 One of the members as shown in Figs. 6 and 7 consists of a strip 30 of metal having one edge 31 turned up and one end turned up and bent over at right angles to form an inturned flange 32. This turned up end is provided with a slot 33 for a purpose to be described. Further the turned up edge 31 is provided with a tongue 34 forming a retaining guide for the second member.

80 The second member (Figs. 8 and 9) is a metal strip 40 of slightly less width than strip 30. This strip has one turned up edge 41 extending the length of its body portion and having a portion extending from one end constituting a tongue 42 adapted to pass through slot 32. The other end of strip 40 is turned up and over at right angles to form an inturned flange 43.

85 The third member (Figs. 10 and 11) consists of a metal strip 50 having one edge 51 turned up as shown and one end turned up and over at right angles to form an inturned flange 52.

90 The fourth member (Figs. 12 and 13) consists of a metal strip 60 having one edge turned up and over to form a retaining guide 61 and one end turned up and over at right angles to form an inturned flange 62.

95 In assembling the device from the four members, the strip 40 will be placed in the strip 30 with its edge 41 under the guide 34 and the tongue 42 through slot 33 to form one side of the binder. The strip 50 will then be placed in the strip 60 with its edge 51 under the guide 61 to form the other side. The latter side consisting of strips 50 and 60 will then be slipped laterally into the side formed of strips 30 and 40 with the flanges 52 and 62 under the flanges 43 and 32, respectively. 100 This assembly is shown in Fig. 14.

105 When the length of the binder has been

adjusted to fit the magazines to be bound, the tongue 42 is preferably cut off to within a short distance of the end 32 and the remaining short end bent over to hold the parts 5 secure.

The modification shown in Fig. 17 differs from that shown in Fig. 5 in that the member 25^a does not extend the full length of member 20^a and the tongue 27^a is upon member 20^a. When the magazines are inserted in the binder and the part 25^a in place, the tongue 27^a is bent up over the end of part 25^a holding it in place. If desired the end 25^b of part 25^a may be slightly turned up so as to 15 put the parts under light tension.

Suitable decorative covers may be applied to the binders and Fig. 15 shows a section of the first mentioned form with such a cover. In this figure, the member 20 is shown as 20 having a piece of cloth 70 glued to the outside and a second piece 71 glued to the inside. The free edges of these two pieces will be glued to opposite sides of two stiffening members 72 as shown.

25 When it is desired to bind the magazines in the devices shown, each magazine is provided with a notch in each of its ends near the back edge as indicated in Fig. 16, this figure representing the back corner of a magazine at 30 80 with a notch at 81. These notches provide seats for the inturned flanges 22 and 26 and 32, 62, 43 and 52, so that when the binding devices are pressed together longitudinally 35 the flanges enter the notches and hold securely the magazines. After the magazines have

been fitted into the binders with the tongue 27 or 42 extending out, the latter is bent over to make a substantially permanent binding.

Having now described the invention and the preferred forms of embodiment thereof, 40 it is to be understood that the said invention is not to be limited to the specific details herein set forth, but only by the scope of the claims which follow.

45 I claim:

1. A binder for magazines or the like comprising two sections each having an inturned flange at one end, one of said sections also having upturned sides and provided with guiding means for the other of said sections, 50 the other of said sections adapted to slide longitudinally within the first, the inner section being provided with a tongue adapted to pass through a slot in the end of the outer section and be bent over to fix the relative positions 55 of the flanges.

2. A binder for magazines or the like comprising two sections each having an inturned flange at one end, and being composed of two laterally adjustable parts one of said sections 60 also having upturned sides and provided with guiding means for the other of said sections, the other of said sections adapted to slide longitudinally within the first, the inner section being provided with a tongue adapted to pass through a slot in the end of the outer section and be bent over to fix the relative positions 65 of the flanges.

HERMAN T. ARENDS.
